UNITED STATES PATENT OFFICE.

HENRY POIRIER, OF NEW BEDFORD, MASSACHUSETTS.

SELF-THREADING SHUTTLE.

Application filed October 26, 1925. Serial No. 64,965.

The present invention relates to loom-shuttles and more particularly to a thread retainer and eye for the threading slot.

It is an object of this invention to provide an improved shuttle eye and thread retainer in a shuttle to permit easy threading and prevent dethreading of the shuttle eye. For this purpose two cylindrical guides disposed at right angles to each other and communicating with the threading slot are provided. One of the guides, hereinafter referred to as the shuttle eye, is disposed in a transverse horizontal passage in the shuttle, while the other guide, or thread-retainer, is placed in a vertical passage communicating with the horizontal passage.

The invention will be more fully understood by reference to the following specification and the drawings, in which:

Figure 1 is a side view of a shuttle provided with a thread-eye of the type embodying the present invention;

Figure 2 is a plan view of the shuttle having a thread-retainer;

Figure 3 is a top view of the thread-eye;

Figure 4 is a front view of the retainer;

Figure 5 is a side view of the retainer; and

Figure 6 is a section on the line 6—6 of Figure 1.

In the preferred form of the invention the shuttle 10 is provided with the usual threading slot 11, a vertical passage 12 and a horizontal passage 13 which intersects and communicates with the passage 12. Disposed within the passage 12 is a cylindrical guide or thread-retainer 14 designed to facilitate easy threading of the shuttle and retain the thread in proper relation to the shuttle eye. The shuttle eye 15 is also substantially cylindrical and is provided with a tortuous slot which permits easy threading but prevents dethreading of the shuttle.

The thread retainer 14 has an axial thread passage 16 extending throughout its length and a radial slot 17 communicating with the passage 16. The lower end of the retainer 14 is cut away to the diametrical plane through the slot 17 as shown in Figures 4 and 5, an inclined face 18 being formed on that side of the retainer which is adjacent the passage 13 when the retainer is placed in the shuttle. The retaining guide is provided with one or more lips 19 which serve to position the guide in the shuttle and prevent its relative rotation with respect to the shuttle.

The shuttle eye 15 has an axial bore or thread passage 20 extending throughout its length and a radial slot 21 communicating with the bore 20. The slot 21 parallels the axis of the passage 20 for a short distance to a point at which it is substantially tangent to an enlarged radial opening 22 in the eye. The continuation 23 of the slot 21 is also tangent to the opening 22 but at a point opposite the portion 21' of the slot. The continuation of the slot is at an angle to the axis of the eye so that it intersects the inner end of the guide directly in line with the slot 21'. It will be seen that a tongue 24 is thus provided, the purpose of which is to prevent radial displacement of the thread after the eye has been threaded. The eye is further provided with a lip 25 to retain it in its proper position with respect to the threading slot 11.

In assembling the shuttle eye and retainer, the parts 14 and 15 are inserted in the passages 12 and 13 respectively, the projecting lips 19 and 25 serving to position the guides to bring the radial slots 17 and 21 into alignment with the threading slot 11 and retain the guides in those positions. The shuttle is threaded by hand, the thread being inserted in the slot 11, after which a slight pull on the thread will cause it to enter the guide slots 17 and 21. Since the axes of the guides 14 and 15 intersect each other the thread will be drawn into the passages 16 and 20 and retained therein, the inclined face 18 of the retainer 14 guiding the thread to the inner end of the slot 21 of the eye 15 while the threading slot 11 guides the thread to the outer end of the slot 21. As is usual in threading slots of the kind shown in the drawings, the slot 11^a is cut in a vertical plane while the slot 11^b is cut in a horizontal plane. In the present invention these slots are cut parallel to the passages 12 and 13 respectively so that the radial slots in the guides are in alignment with the threading slot when the parts have been assembled and the thread can be readily drawn into the guides 14 and 15. The slot in the eye 15 is of such form that after the thread has been drawn into the eye it cannot be withdrawn through the slot 21, thus insuring retention of the thread in the shuttle eye while the shuttle is in motion.

Although the invention has been described in detail, it is obvious that it may be modified. It is therefore not intended that the

invention be limited to the exact construction illustrated but includes such changes as come within the scope of the appended claims.

5 Having thus described the invention, what is claimed as new and desired to be secured by Letters Patent is:

1. In a shuttle having a hand-threading slot, a vertical thread passage, a horizontal thread passage communicating with and intersecting said vertical passage, said threading slot intersecting each of the thread passages in a plane parallel to the axis thereof, cylindrical thread guides, one in each of said passages, said vertical guide having a radial slot in alignment with the threading slot, and said horizontal guide being provided with a tortuous slot the ends of which are in alignment with a common element of the guide and with the threading slot, whereby dethreading of the shuttle is prevented.

2. A thread eye for shuttles comprising a member having an axial bore, a substantially circular radial opening intermediate the ends of said member, and a radial slot connecting each end of said member with said opening, each of said slots being tangent to said opening but at different points on its circumference.

3. In a shuttle having a hand-threading slot, a vertical thread passage, a horizontal thread passage communicating with and intersecting said vertical passage, said threading slot intersecting each of the thread passages in a plane parallel to the axis thereof, thread guides in each of said passages, said vertical guide having a radial slot in alignment with the threading slot and a cutaway portion at its lower end in communication with the radial slot and disposed adjacent the horizontal passage said cut away portion having an inclined upper edge disposed below the upper edge of the guide in the horizontal passage and said horizontal guide being provided with a tor-

tuous slot, the ends of which are in alignment with a common element of the guide and with the threading slot, the lower end also being disposed adjacent the cutaway portion of the vertical guide, whereby dethreading of the shuttle is prevented.

4. A thread eye for shuttles, comprising a cylindrical member having an axial bore, a substantially circular radial opening intermediate the ends of said member, and a radial slot connecting each end of said member with said opening, each of said slots being tangent to said opening but at different points on its circumference, one of said slots being disposed substantially along elements of the cylindrical member throughout its length.

5. A thread eye for shuttles, comprising a cylindrical member having an axial bore, a substantially circular radial opening intermediate the ends of said member, and a radial slot connecting each end of said member with said opening, each of said slots being tangent to said opening but at different points on its circumference, the ends of said slots being disposed substantially along common elements of the cylindrical member.

6. A thread eye for shuttles, comprising a cylindrical member having an axial bore, a substantially circular radial opening intermediate the ends of said member, and a radial slot connecting each end of said member with said opening, each of said slots being tangent to said opening but at different points on its circumference, the ends of said slots being disposed substantially along common elements of the cylindrical member and one of said slots being disposed substantially along elements of the member throughout its length.

In testimony whereof I hereunto affix my signature.

HENRY POIRIER.
